UNITED STATES PATENT OFFICE

2,054,104

RENEWABLE BLADE KNIFE

Russell Edgar Smith, Belleville, Ontario, Canada

Application June 10, 1935, Serial No. 25,863

1 Claim. (Cl. 30—9)

The invention relates to a knife and more especially to a renewable bladed knife.

The primary object of the invention is the provision of a knife of this character, wherein a ribbon blade is carried in a position thereby so that the said blade can be fed to present to the knife a fresh cutting edge to assure a continued maintenance of a sharp cutting edge in that when a presented edge becomes dull a sharpened edge will be caused to take the place thereof and in this fashion the knife will be in a continued sharpened condition for service without necessitating sharpening thereof.

Another object of the invention is the provision of a knife of this character, wherein the ribbon cutting blade is mounted in the knife in a novel manner so that the blade may be fed in cutting position and thus the knife is assured of sharpness in the continued or repeated uses of the same, the knife in its entirety being of novel construction.

A further object of the invention is the provision of a knife of this character, which is simple in construction, reliable and efficient in operation, assured of a continuity of sharpened condition, strong, durable and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

35 In the accompanying drawing:

Figure 1 is a side elevation of a knife constructed in accordance with the invention and the same being partly broken away.

Figure 2 is a horizontal sectional view taken longitudinally of the knife.

Figure 3 is a sectional view on the line 3—3 of Figure 1 looking in the direction of the arrows.

Figure 4 is a sectional view on the line 4—4 of Figure 1 looking in the direction of the arrows.

Figure 5 is a fragmentary horizontal sectional view showing in detail a spur guide wheel for the blade of the knife.

Similar reference characters indicate corresponding parts throughout the several views in the drawing.

Referring to the drawing in detail, the knife comprises a blade stock 10 and a handle stock 11, respectively, the handle stock being longitudinally split to provide complementary parts, these

being joined by nut carrying bolts 12 which are passed transversely through the complementary parts of the stock 11 and through suitable openings in the blade stock 10 which is arranged between the said parts at its end carrying the handle stock, each head 13 and nut 14 of the bolt being countersunk in the parts of said handle stock 11.

Formed in the parts of the handle stock 11 is a magazine or chamber 15 for accommodating 10 a coiled flexible ribbon-like cutting blade 16, the magazine or chamber being communicative with a way 17 provided in the parts of the stock 11 which is carried longitudinally through the lower edge of the blade stock 10 and opens through 15 the free end thereof remote from or opposite the handle stock end. This way 17 opens through the lowermost edge or what might be termed the cutting edge of the blade stock 10 to expose the blade 16 therethrough which blade has the knife or cutting edge 18. It is preferable to have the edge carrying the blade 16 at opposite outer sides thereof reversely beveled at 19 to thin the blade stock in conformity with the cutting edge or knife 18 of the blade 16.

Rotatably journaled in one part of the handle stock 11 at one side of the blade 16 is a horizontally disposed spur feed wheel 20, its spurs 21 being in meshing engagement with holes 22 provided in the blade 16 in a row and equally distanced in spaced relation to each other. The arbor or axle 23 for the wheel 20 is adjustable and is held within a barrel 24 fitted in the handle stock 11 so that the screw driver engaged end 25 of such arbor is exposed without the handle stock and the barrel 24 whereby the arbor 23 through the use of a screw driver (not shown) can be turned so that the open wheel 20 will function as a feeder for the blade 16 to extend the same through the way 17 and in this fashion a fresh or sharper edge 18 of the blade can be exposed from the knife stock 10.

This knife stock 10 has formed therein an elongated slot 26 at one side of the way 17 and this slot 26 is in alignment with the row of 45 holes 22 in the blade 16 so that pins or the like may be passed through the holes 22 that register with the end walls provided by the slot 26, to hold the said blade taut, or when such pins are removed to permit a pointed implement or tool 50 to be passed through the slot 26 to selectively engage the holes 22 for assisting in the feed of the ribbon blade 16 through the way 19 in the knife stock. This blade 16 is made from tempered steel of ribbon or strip form. The blade 55

16 can be of any desired length and the portion not exposed through the knife stock 10 will be in a coiled wound condition and confined within the magazine or chamber 15 in the handle stock 11 of the knife, the unwinding of the blade 16 being had by the feed wheel 20 and by an implement when inserted in the slot 26 to engage selectively the holes 22 in the row thereof in said blade 16.

10. What is claimed is:

In a device for the purpose set forth, a handle having a chamber therein, a blade stock extending longitudinally from the handle and having a grooved edge providing a way for a flexible

knife blade and said handle having a slot for the passage of the blade into the chamber in said handle and the portion of the blade received in the chamber of the handle being coiled upon itself, said blade having a series of equidistantly spaced holes adjacent to its inner or back edge, a toothed wheel journaled in the handle to engage with certain of the holes in the blade, a turning shaft having an outer kerfed end for turning the wheel, said blade stock adjacent to its outer end having a transverse elongated slot therethrough in a line with the holes in the blade, and for the purpose set forth.

RUSSELL EDGAR SMITH.
